OVERSHOE

Chester H. Haines, Gardena, and Dolph G. Hoyt, Jr., Los Angeles, Calif., assignors to Coffey-Hoyt Products, Inc., Gardena, Calif., a corporation of California

Application June 27, 1952, Serial No. 20,380

Term of patent 14 years

(Cl. D7—4)

To all whom it may concern:

Be it known that we, Chester H. Haines and Dolph G. Hoyt, Jr., citizens of the United States, residing in Gardena, in the county of Los Angeles, State of California, and in Los Angeles, in the county of Los Angeles, State of California, respectively, have invented a new, original, and ornamental Design for an Overshoe, of which the following is a specification, reference being had to the accompanying drawing, forming a part thereof.

The figure is a bottom view of an overshoe embodying our design, with a portion of the top of the overshoe illustrated in broken lines as partially folded to one side.

The dominant features of our design reside in the portions shown in full lines.

We claim:

The ornamental design for an overshoe, substantially as shown and described.

CHESTER H. HAINES.
DOLPH G. HOYT, JR.
